UNITED STATES PATENT OFFICE.

AVERY W. BILLINGS, OF LARNED, ASSIGNOR OF TWO-THIRDS TO ARTHUR T. BILLINGS AND WILLIAM G. BILLINGS, BOTH OF JETMORE, KANSAS.

ROTARY ENGINE.

SPECIFICATION forming part of Letters Patent No. 363,719, dated May 24, 1887.

Application filed December 16, 1886. Serial No. 221,748. (No model.)

To all whom it may concern:

Be it known that I, AVERY W. BILLINGS, a citizen of the United States of America, residing at Larned, in the county of Pawnee and State of Kansas, have invented certain new and useful Improvements in Rotary Engines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to rotary engines.

The object of the invention is to simplify the construction and operation of devices of this class, thereby materially decreasing the cost.

To this end the invention consists in novel 20 arrangements and constructions, which will be fully described in the ensuing specification, and set forth in the claims at the close thereof.

In the accompanying drawings, Figure 1 is a vertical section through the cylinder and piston taken at right angles to the piston-shaft. 25 Fig. 2 is a vertical section taken on line *xx*, Fig. 1. Fig. 3 is a horizontal section taken on line *yy*, Fig. 1. Fig. 4 is an end elevation of the engine. Fig. 5 is a side elevation of one of the cam-disk. Fig. 6 is a perspective view of 30 one of the folding gates with its operating-crank. Figs. 7 and 8 are detail perspectives of one of the pitman-abutments.

The engine-cylinder rests upon a base, A, 35 and is composed of an annular shell, B, and heads C C', fitted steam-tight. In the drawings I have represented the base A as formed integral with the ring A; but it will be understood that it may be otherwise. The heads C 40 C' are provided centrally with outwardly-extending hubs forming bearings for the shaft D of the annular piston D'. This piston is arranged concentrically within the annular shell B of the cylinder, with its edges fitting closely 45 against the cylinder-heads C C', and the hub *d* of the piston is fitted closely between the cylinder-heads C C', and is keyed or otherwise rigidly secured to its shaft, any suitable form 50 of packing being used to prevent any escape of steam between the piston and cylinder heads and through the shaft-bearings.

The shell B of the cylinder is provided at opposite points with recesses *b* to receive abutments B' B'', pivoted between the heads C C', and adapted to bridge the steam-space between the shell B and the piston D'. The shafts of these abutments B' B'' are extended through the cylinder-head C' and fitted with crank-arms *b' b''*, the purpose of which will be hereinafter explained. The engine illustrated in 60 the drawings is represented as having two of these abutments B' B'' arranged on opposite sides of the cylinder and just in advance of the two oppositely-arranged steam-induction ports *c c'* in the cylinder-head C, the eduction 65 or exhaust ports *c' c''* being also arranged opposite each other and in a plane at right angles to the plane of the induction-ports *c c'*. The piston D' is provided with three radial projections, *d' d'' d'''*, which I shall hereinafter 70 term "piston-heads," moving in contact with the shell B and heads C C' of the cylinder.

Opposite the head C' of the cylinder is a disk, E, keyed to the projecting end of the shaft D, said disk being provided with a cam-groove, *e*, facing said head to receive the outer end of the crank-arms *b' b''* of the hinged abutments B' B'', another cam-disk, F, being keyed to the opposite end of the shaft D to actuate a valve-lever, G, controlling steam-valves (not 80 shown) in the branches *h h'* of steam-pipe H.

The cam-disk F is so constructed and arranged with relation to the piston-heads *d' d'' d'''* that steam will be admitted through branch *h'* of the steam-pipe H and port *c'* just as one or 85 the other of the piston heads has passed said port, and through branch *h* and port *c* just as piston-heads pass latter port, the valve-stem *g* being shifted from side to side by the cam-disk F and valve-lever G, according to the position of the piston-heads. While these actions are taking place, and just before a piston-head reaches one or the other of the hinged abutments B' B'', the latter will be alternately turned, through the agency of crank-arms *b' b''* 95 and cam-disk E, to lie closely within the recess *b* of the cylinder-shell B, thus permitting the free passage of said piston-head, when the abutment will be again turned to bridge the steam-space between the cylinder-shell B and 100 the piston. To illustrate, we will suppose that the piston is traveling in the direction of the

arrow, Fig. 1. In the position shown, steam has just been shut off from branch h' of the steam-pipe and induction-port c' and admitted through branch h and port c . The steam, being confined between abutment B' and piston-head d' and between abutment B^2 and piston-head d^2 , will impel said piston-heads toward the exhaust ports c^2 c^3 , and as the piston-head d^2 reaches the abutment B^2 the latter will be turned by cam-disk E and crank-arm b'' back into recess b , thus permitting the piston-head to pass. Piston-head d^2 having passed abutment B^2 , the latter will be again turned to bridge the steam-space, when steam will be shut off from port c , admitted through port c' , and exhausted through ports c^2 c^3 .

The inner surfaces of the heads C C' and shell B of the cylinder are cut away slightly between the exhaust-port c^2 and the adjacent abutment B' and between port c^3 and abutment B^2 , as shown at B^3 , Fig. 1, to permit the piston-heads to traverse this space without friction, and also to permit the escape of exhaust steam from in front of a piston-head as it approaches the abutment; but between abutment B' and port c^3 and between abutment B^2 and port c^2 the cylinder-heads are provided with packings C^3 , in contact with which the edges of the piston travel.

Each piston-head consists of two angle-boxes, I, a coupling-plate, I', and a packing, I². These boxes I are triangular in cross section, their outer edges, i , terminating in sharp angles, as shown, and the inner bottom corners having perforated lugs to receive the pivot-pin by which they are connected to the coupling-plate I'. Two of these boxes I being coupled together by the plate I', a packing of suitable size, shape, and material (preferably asbestos) is inserted between the vertical sides of the two boxes. The piston-heads are now applied to the piston by inserting their outer sharp edges, i , beneath the overhanging edges or walls of transverse dovetailed grooves d^4 in the face of the piston, passing clamping-bolts i' through apertures in said piston and securing the nuts i'' . As the packing I² becomes worn by friction against the shell of the cylinder, it may be adjusted by tightening up the nuts i'' , thus drawing the vertical sides of the boxes nearer together and compressing the packing more tightly.

It is intended that the base of the piston-heads shall not rest upon the surface of the piston ordinarily, but be bowed upward there-

from, said heads being held firmly in place by the engagement of their outer corners beneath the overhanging walls of the grooves d^4 and by the bolts i' . Now, as the packing held between the vertical faces of the respective heads becomes worn, the nuts i'' are turned upon the bolts i' to draw the coupling-plate I' at the center of each head nearer to the surface of the piston, thus causing the sharp outer edges, i , of the heads to move asunder and further beneath the overhanging edges of the groove, and also causing the vertical faces or sides of the two boxes composing each head to approach each other, thus compressing the packing held between said faces and forcing it outward toward the cylinder-heads and shell.

I claim—

1. In a rotary engine, the combination of the cylinder provided at opposite points with induction-ports and hinged abutments adjacent thereto, the exhaust-ports arranged oppositely and in a plane vertical to the plane of the induction-ports, and the piston provided with heads arranged as shown with relation to each other, substantially as described.

2. The combination of the cylinder provided at opposite points with induction-ports and recesses abreast said ports, the exhaust-ports arranged oppositely and in a plane vertical to the induction-ports, the piston provided with heads, and the hinged abutments constructed to bridge the steam-space in the cylinder or to fold within the recesses of said cylinder, substantially as described.

3. The combination of the cylinder, the piston having heads, induction ports arranged at opposite points in the cylinder-head, the exhaust-ports arranged oppositely and in a plane vertical to the plane of the induction ports, and the hinged abutments, the cylinder being cut away, as at B^3 , substantially as and for the purpose stated.

4. The combination, substantially as described, of the cylinder with its ports and abutments, the piston having heads, the cam-disk E, to rotate the abutments, and the cam-disk F, controlling the admission of steam to the ports of the cylinder.

In testimony whereof I affix my signature in presence of two witnesses.
